UNITED STATES PATENT OFFICE.

WALLACE A. FRENCH, OF SAN DIEGO, CALIFORNIA.

RACE-HORSE-STARTING-GATE APPARATUS.

Application filed May 17, 1924. Serial No. 713,955.

To all whom it may concern:

Be it known that I, WALLACE A. FRENCH, a citizen of the United States, residing at San Diego, in the county of San Diego and 5 State of California, have invented a certain new and useful Race-Horse-Starting-Gate Apparatus, of which the following is a specification.

My invention relates to a race horse starting gate apparatus, and the objects of my invention are: first, to provide an apparatus of this class whereby the gate or barrier, against which horses are adapted to stand, may be easily and quickly shifted out of the 15 way when desiring to start the horses in a race; second, to provide an apparatus of this class whereby the horses bearing against the barrier in any direction will not distort the apparatus or trip the same; third, to 20 provide novelly constructed carriage means for shifting the flexible barrier; fourth, to provide novel latch and release or trip means for the barrier; fifth, to provide a novel means in connection with the flexible barrier whereby the same is automatically separated when too much force is exerted against the same by the horses; sixth, to provide a race horse starting gate apparatus which may be easily and quickly 25 folded when desired, for transporting the same; seventh, to provide as a whole a novelly constructed race horse starting gate apparatus, and eighth, to provide an apparatus of this class which is simple and 30 economical of construction, durable, efficient, rapid and reliable in its action, and which will not readily deteriorate or get out of order.

With these and other objects in view, as 35 will appear hereinafter, my invention consists of certain novel features of construction, combination and arrangement of parts and portions, as will be hereinafter described in detail and particularly set forth 40 in the appended claims, reference being had to the accompanying drawings and to the characters of reference thereon, which form a part of this application, in which:

Figure 1 is a side elevational view of one 45 side of my starting gate apparatus positioned on one side of a race-track, against and on the one fence surrounding the same,

showing by dotted lines the folded positions of certain of the main members; Fig. 2 is a fragmentary end elevational view 55 thereof, showing the apparatus at both sides of the track; Fig. 3 is a fragmentary enlarged side elevational view of the frame supporting the tripping mechanism, barrier carriage and other members at one side of 60 the track; Fig. 4 is a fragmentary view thereof taken at 4-4 of Fig. 3; Fig. 5 is another fragmentary view thereof taken at 5-5 of Fig. 4, and Fig. 6 is a perspective 65 view of the barrier separating means secured to adjacent ends of the flexible barrier member.

Like characters of reference refer to similar parts and portions throughout the several views of the drawings.

The frame members 1, 2, 3, 4 and 5, brace members 6, 7, 8, 9 and 10, pins 11, 12 and 13, supports 14, tie cables 15, guys 16, tripping mechanism casing 17, tripping member 18, rollers 19 and 20, tripping lever 21, spring 75 22, pin 23, slide 24, bumper 25, guide 26, pulleys 27, 28 and 29, cables 30 and 31, barrier carriage release members 32, tension springs 33, barrier carriages 34, roller supports 35, rollers 36, ball bearing rollers 37, 80 clevis members 38, bolts 39, barrier member 40, barrier separating means 41, pulleys 42, cables 43, elastic members 44, tripping cable 45, and the pulley 46, constitute the principal parts and portions of my race horse starting 85 gate apparatus.

My starting gate apparatus consists of two supporting units, one positioned at each side of the race track, for supporting a shiftable barrier over the track. The supporting frame members 1, 2, 3 and 4 of each unit are preferably built up of angle iron, forming channels. The frame members 1 are supported at the upper ends of supports 14, preferably pipe, which are preferably secured to the upper and lower rails of the fence F bordering the race-track, by means of tie cables 15. At the near and far ends of each frame member 1 are permanently secured short upright frame members 2 and 3, respectively, which are braced relatively to the member 1 by the brace members 6 and 7. Near the upper end of the member 2 is pivotally connected, by means of the pin 12,

the one end of the frame member 5, which is preferably built up of a pair of small, spaced apart, oppositely disposed channels, which are provided at their outer sides with 5 angles. The flanges of said channels extend toward each other forming partially enclosed tracks for the rollers 37, which will be described later. The upright frame member 4 is pivotally connected at its lower end 10 intermediate the ends of the frame member 3 by means of the pin 11. Near the upper end of the member 4 are provided longitudinal slots 4^a in which are adapted to be positioned the outwardly extending pins 13 at 15 the upper or forward end of the frame member 5. The frame member 5 is held in position at its upper end against the upper end of the frame member 4 by means of the brace member 8, which may be a wire or 20 cable and may be provided intermediate its ends with a turnbuckle. The supporting frame, as described, is braced at its near end relatively to the fence F by means of an adjustable brace member 9, and is similarly 25 braced, at the side facing the race track, by means of the adjustable brace member 10, as shown best in Figs 1 and 2 of the drawings. Said supporting frames are braced at their outer sides by means of guys 16.

30 The frame members 5, which are supported at their near ends on the short upright frame members 2 and at their far ends at the upper ends of the frame members 4, are positioned diagonally in such a 35 manner as to provide an upwardly and forwardly directed track for the barrier carriages, adapting the barrier, when released, to be shifted upwardly and forwardly from the noses of the horses positioned near the 40 same. At the lower inner side of one of the frame members 5 is mounted a tripping mechanism casing 17 in which are positioned a pair of rollers 19 and 20, between which is reciprocally mounted the tripping or 45 latch member 18, which extends above the casing 17. Within said casing is pivotally mounted the tripping lever 21 in the form of a bell crank, the one end of which extends into a recess at the inner end of the member 18. The tripping member 18 is held in an outward position by means of a tension spring 22 secured at its one end to the bell crank 21 and at its other end to a pin 23 holding the member 18 in position. 50 In front of the casing 17 is mounted a guide 26 on which is reciprocally mounted a slide 24, which is provided at its near or rear end with a hole through which the outer end of the member 18 is adapted to extend 55 for holding the slide 24. Near the forward end of the slide 24 is provided a downwardly extending lug to which is secured a rubber bumper 25, which is adapted to engage the forward end of the guide 26 when the former is released. At the sides of the slide 60

24 are secured the one ends of the cables 30 and 31, the former of which extends around pulleys 27 and 29 to the apparatus at the other side of the track. The other cable 31 extends around a pulley 28 and 70 backwardly around another pulley 27 and is connected at its other end with the outer end of the carriage releasing bell crank member 32, which is pivotally mounted between the channels of the frame member 5. 75

The carriages 34 for supporting and shifting the flexible barrier member, consist of rectangular frames in which are positioned pairs of ball bearing rollers 37, which are mounted on studs 37^a. To the rear ends of the carriage frames 34 are secured U-shaped roller supporting members 35 which are provided at their outwardly extended ends with rollers 36. The one arms of the bell crank members 32 are provided with hook portions 32^a which are adapted to engage the rollers 36 and hold the carriages in a retracted position. To the outwardly extending arms of the carriage releasing bell crank members 32 are secured the one ends of tension springs 33, which are removably secured at their other ends to the upper ends of the frame members 2. There are provided bolts 5^a which extend transversely 85 through the frame members 5 for limiting the backward movement of the carriages 34, and which engage the upper sides of the U-shaped members 35 to prevent the same from being tilted when the flexible barrier is engaged by the horses. To the upper and 90 lower sides of the frames of the carriages 34 are pivotally mounted the one ends of the clevis members 38 by means of bolts 39. At the inner ends of the clevis members are provided eye bolts to which are secured the 95 ends of the flexible barrier member, which may be made of rope, cable or fabric tape.

Intermediate the ends of the barrier member or at one end thereof is positioned a barrier separating means 41, as illustrated in Fig. 6 of the drawings, which consists primarily of a pair of spaced apart spring members 41^a, with converging ends, between the converging ends of which are adapted to 110 be removably positioned the diverging ends of a pair of clips 41^b secured together in any convenient manner. The lateral sides or edges of the clips 41^b are preferably beveled so that the same may be readily inserted between the diverging resilient ends of the members 41^a. It will be noted that when a force greater than that desired is exerted by the horses against the barrier member, the spring members 41^a will be separated, permitting the members 41^b to be withdrawn. 115

At the upper ends of the frame members 4 are revolvably mounted pulleys 42 over which extend cables 43, which are secured at their one ends to the forward ends of the frames of the carriages 34 and at their op- 120 125 130

posite ends to the one ends of springs or elastic members 44, which elastic members are secured at their opposite ends to the fence F at a spaced distance from the supporting frames of the apparatus. It will be noted that there are preferably provided bumpers at the upper ends of the frame or track members 5 to take up the shock of the carriages when the same are released.

10 The tripping mechanism is preferably tripped by means of a cable 45, which extends around a pulley 46 mounted on one of the frame members 5 contiguous to the tripping means.

15 When desiring to set the barrier in the downward or operative position, the tension springs 33 at both sides of the apparatus are preferably released at their one ends. The carriages are then drawn backwardly until 20 the hook portions 32^a at both sides of the apparatus are positioned over the rollers 36, which hold the barrier carriages against the tension of the elastic 44. The springs 33 are then secured at their free ends, as previously 25 stated, thus setting the apparatus ready for action to release the barrier. When the cable 45 is pulled, the tripping member 18 on the one side of the apparatus is withdrawn, permitting the slide 24 to be pulled forwardly by the springs 33 on both sides of 30 the apparatus. Such action of the slide releases the cables 30 and 31 connected thereto, which in turn permit the carriage release bell crank members at each side of the apparatus 35 to be tilted backwardly about their pivotal mountings by the springs 33, releasing the carriages 34. The carriages on both sides of the apparatus, being thus released, are simultaneously shifted forwardly and upwardly by the elastic members 44 on both sides of the apparatus, shifting the flexible barrier out of the way and permitting the horses stationed at the barrier to proceed.

40 It will be here noted that when desiring to transport the apparatus from one place to another, the same may be readily collapsed by releasing the adjustable brace member 8, raising the frame member 5 slightly, folding the upright frame member 4 downwardly and then folding the frame member 5 over the frame member 4 against the upper end of the short frame member 3, substantially as shown by dotted lines in Fig. 1 of the drawings.

45 It is obvious from this construction, as illustrated in the drawings and disclosed in the foregoing specification, that there is provided a race horse starting gate apparatus as aimed at and set forth in the objects of the invention, and though I have shown and described a particular construction, combination and arrangement of parts and portions, I do not wish to be limited to this particular construction, combination and arrangement, but desire to include in the scope

of my invention the construction, combination and arrangement substantially as set forth in the appended claims.

Having thus described my invention, what I claim as new and desire to secure by Letters Patent, is:

1. In an apparatus of the class described, a pair of spaced apart, readily foldable, substantially triangular rigid frames provided with angular tracks on one of the foldable members of each frame, roller carriages mounted on said tracks, a flexible barrier member secured to and shiftable by said carriages, a means for holding and readily releasing said carriages, and resilient means for shifting said carriages when released.

2. In a race horse starting apparatus, a pair of spaced apart frames provided with angular tracks consisting of spaced apart channels, carriage frames positioned between the channels of said tracks, rollers revolvably mounted on said carriage frames between said channels, clevis members pivotally mounted on said carriage frames, a flexible barrier member secured to the free ends of said clevis members, a tripping plunger means mounted near one end of one of said tracks, a longitudinal guide positioned contiguous to said tripping plunger means, a slide mounted on said guide, carriage releasing lever means pivotally mounted contiguous to said tracks adapted to engage and hold said carriage frames, and cables connecting said slide with the carriage releasing lever means in connection with both of said tracks.

3. In a race horse starting apparatus, a pair of spaced apart frames provided with angular tracks consisting of spaced apart channels, carriage frames positioned between the channels of said tracks, rollers revolvably mounted on said carriage frames between said channels, clevis members pivotally mounted on said carriage frames, a flexible barrier member secured to the free ends of said clevis members, a tripping plunger means mounted near one end of one of said tracks, said tripping plunger means consisting of a casing, a plunger reciprocally mounted therein, rollers on opposite sides of said plunger, a bell crank pivotally mounted in said casing, the one arm thereof engaging said plunger, and a spring means adapted to force said plunger outwardly, a longitudinal guide positioned contiguous to said tripping plunger means, a slide mounted on said guide, carriage releasing lever means pivotally mounted contiguous to said tracks adapted to engage and hold said carriage frames, and cables connecting said slide with the carriage releasing lever means in connection with both of said tracks.

4. In a race horse starting apparatus, a pair of spaced apart main frames provided with angular tracks consisting of spaced

apart channels, carriage frames positioned between the channels of said tracks, rollers revolvably mounted on said carriage frames between said channels, clevis members pivotally mounted on said carriage frames, a flexible barrier member secured to the free ends of said clevis members, a tripping plunger means mounted near one end of one of said tracks, a longitudinal guide positioned contiguous to said tripping plunger means, a slide mounted on said guide, carriage releasing lever means pivotally mounted contiguous to said tracks adapted to engage and hold said carriage frames cables connecting said slide with the carriage releasing lever means in connection with both of said tracks, removable tension springs secured to said carriage releasing lever means and to said main frames, and resilient means secured to said carriages adapted to shift the same when released.

5. In a race horse starting apparatus, a pair of spaced apart frames provided with angular tracks, carriages reciprocally

mounted on said tracks, a flexible barrier means connecting said carriages, means for holding and readily releasing said carriages, and trip means in connection with one of said frames adapted to trip said holding and releasing means. 30

6. In a race horse starting apparatus, a pair of spaced apart frames provided with angular tracks, carriages reciprocally mounted on said tracks, a flexible barrier means connecting said carriages, means for holding and readily releasing said carriages, trip means in connection with one of said frames adapted to trip said holding and releasing means, a yieldable means adapted to 35 shift said carriages when released, and a spring means in connection with said holding and releasing means adapted to shift the same when the tripping means is actuated. 40

In testimony whereof, I have hereunto set my hand at San Diego, California, this 9th day of May, 1924. 45

WALLACE A. FRENCH.
